SHIFT REGISTER

John C. Mallinson, Palo Alto, Calif., assignor to
AMP Incorporated, Harrisburg, Pa.Continuation of application Ser. No. 50,695, Aug. 19,
1960. This application Apr. 10, 1964, Ser. No. 360,167

1 Claim. (Cl. 340—174)

This invention relates to a magnetic core memory device, and more particularly to an improved and simplified shift register. This application is a continuation of my earlier filed application, Serial No. 50,695 filed August 19, 1960, and entitled Shift Register, now abandoned.

An object of the invention is to provide a magnetic core memory and signal translating device having improved performance and operation over a wide temperature range.

Another object is to simplify the wiring of a shift register.

A further object is to provide a wiring scheme for a shift register which lessens the electrical drive requirements of the register.

These and other objects will in part be understood from and in part pointed out in the following description.

In U.S. Patent No. 2,995,731 to J. P. Sweeney, there is disclosed an improved shift register wherein a number of multi-aperture magnetic cores are connected in sequence for the transfer from one core to the next of a binary "one" or "zero." One core is connected to the next by a respective coupling loop which is threaded through a minor output aperture of the one core and through the major aperture of the next. All of the cores are linked by three drive windings, two of these being "advance" windings and the other, a "prime" winding, which for operation of the register are energized in sequence by respective current pulses.

This shift register circuit is much more stable and reliable in its operation than earlier shift registers, but even so it has certain limitations. Each coupling winding between two successive cores has no blocking diode in it and thus would permit an advance drive pulse applied to a succeeding core to act adversely on the preceding one. To prevent this, the cores are provided with a "hold" winding in addition to the drive windings. The hold winding is in series with the advance windings and serves to apply, to the proper cores in the register, when an advance pulse is applied to either advance winding a magnetic field counteracting and canceling out the field induced on the preceding cores by the coupling windings. This arrangement works quite well but the need for the hold winding imposes an important restriction. For best operation of the register there should be unity turns-ratio between the hold and advance windings. However, the hold winding must be threaded through the minor output apertures of the cores and because these apertures are small (about the size of a pin) only a limited number of turns of the hold winding can be threaded through. This, assuming a given turns-ratio of hold to advance windings, limits the number of turns for the latter. Thus, though it would in many instances be desirable to use a large number of turns for the advance windings to reduce the drive currents or to permit the use of higher drive core materials, this previously has not been possible. The present invention eliminates the need for a hold winding and permits a much larger number of turns for the advance windings.

In accordance with the present invention, in one specific embodiment thereof, individual multi-aperture cores of a shift register are connected from one core to the next by coupling loops uniquely wound on the cores so that even though no blocking diode is used in the loop, there

is still no tendency for one of the driving pulses to feed backward from one core to the preceding one. This eliminates the need for a hold winding and permits a much larger number of advance winding turns on each core, these turns being threaded through the major aperture and thus being applied easily. Because the need for the hold winding is eliminated, there are no residual errors in compensating the unwanted field and this circuit operates reliably over a wider temperature range than previous ones including the shift register in aforesaid patent.

A better understanding of the invention together with a fuller appreciation of its many advantages will best be gained from the following description given in connection with the accompanying drawings wherein:

FIGURE 1 is a schematic representation of a shift register embodying features of the invention;

FIGURE 2 is a wiring diagram of the shift register; and

FIGURES 3a, b, c, d and e are diagrams showing the conditions of the magnetic lines of flux in the various cores of the register after each successive drive pulse.

The shift register 10 shown in FIGURE 1 comprises a number of multi-aperture ferrite cores which are divided into "odd" (O) and "even" (E) groups. For simplicity, only two O cores and one E core are shown but it is to be understood that in a complete shift register there can be a considerable number of cores, with an equal number of cores in each group. The physical layout and general wiring configuration of this shift register can be generally the same as for the one disclosed in the aforesaid patent. Here, the first O core, designated by numeral 11, and having a relatively large major aperture 12, and a small minor aperture 13 is provided with an input winding 14 which is threaded once through aperture 13. Wound twice through this same aperture in the relative sense shown is a coupling loop 16 whose other end is threaded once through the minor aperture 17 of E core 18. Similarly, aperture 17 of core 18 has two turns of the next coupling loop 20 which connects this core to the next core in the register, O core 21, through its minor aperture 22, successive cores in the register (not shown) being connected by coupling loops in the same way.

Each of the minor apertures 13, 17 and 22 of the cores shown, receives three turns of a prime winding 24 which after passing through all of the minor apertures makes a single pass in reverse direction through all of the major apertures of the cores. This winding 24, also shown in FIGURE 2, is adapted to be energized during operation of the register by a relatively long, small amplitude priming pulse.

Wound N number of turns through the major aperture of each O core in the register is an advance winding 26 and similarly wound N turns through the major aperture of each E core is an advance winding 28. It will be noted that in register 10 prime winding 24 is not in series with the advance windings, though, of course, they can have a common ground connection as shown in FIGURE 2. Furthermore, advance winding 26 threads only the O cores and advance winding 28, only the E cores.

Assuming that all of the cores are initially in the "clear" state, that is, saturated with flux in the clockwise direction and that the first core, O core 11, has been set by means of a suitable current pulse applied to winding 14, then the lines of flux in the various cores will be as indicated by the short arrows in FIGURE 3a. In this condition, all of the lines of flux in cores 18 and 21 are clockwise, but half of the lines of flux in core 11 are counter-clockwise. Thereafter, when a prime current is applied to winding 24, certain lines of flux in the cores, indicated by the double-headed arrows in FIGURE 3b will be reversed, the other single-headed arrows remain-

ing the same as they were in FIGURE 3a. Next, applying an advance O to E pulse to winding 26 causes the flux to change as indicated by the double-headed arrows in FIGURE 3c. The next prime pulse causes the change shown in FIGURE 3d and finally, an advance E to O pulse applied to winding 28 causes the change indicated in FIGURE 3e. This completes a full cycle or shifting sequence for the register and the binary "one" previously stored in core 11 has now been advanced to core 21.

It will be noted in FIGURE 1 that coupling loop 16 encircles the outer leg of the core at minor aperture 13 and the inner leg at minor aperture 17 of core 18 in the relative senses indicated. A one-to-one turns ratio in the coupling loop can be used, but two-to-one ratio as shown, insures that the flux switched about minor aperture 13 will cause the same amount of flux to be switched about aperture 17, and so on. Thus, there will be no loss in the amount of flux transferred from core to core along the register.

This coupling loop configuration prevents an advance pulse applied to a core from feeding flux backward through a coupling loop, whilst still permitting forward flux transfer. To understand this more readily, consider the flux in E core 18 after the advance O to E pulse. The lines of flux about minor aperture 17, as indicated in FIGURE 3c, will be in the set state, that is, the flux in the inner leg will be up or counter-clockwise, and the flux in the outer leg down or clockwise. Priming causes the flux to reverse about minor aperture 17, as indicated in FIGURE 3d, and now the flux in the inner leg is down or clockwise. Thus, when the advance E to O pulse is applied, the flux in the inner leg of the core at minor aperture 17 is already clockwise and cannot be changed, only the counter-clockwise flux in the outer leg can be switched. Since no flux in the inner leg switches during this advance E to O pulse, no current is induced in coupling loop 16 and hence no flux in the preceding core 11 can be switched. Thus, there is no need of a hold winding in this circuit.

In a circuit, like the one above, which has been built and successfully operated, multi-aperture cores about the size of a small shirt button and made of type 5209 ferrite material manufactured by General Ceramics Company, were used. Six turns of the advance winding on a core permitted good operation of the register with a peak pulse current of less than 3 amperes. This register is simpler to build and has better operating characteristics than previous registers.

The above description is intended in illustration and not in limitation of the invention. Various changes may occur to those skilled in the art and these may be made without departing from the spirit or scope of the invention as set forth.

I claim:

A shift register circuit for transferring binary intelligence in a controlled manner comprising a plurality of multiaperture magnetic cores each having a major aperture and a minor aperture, the said cores being divided into odd and even groups and threaded by a drive circuit capable of applying drive current to said cores to advance intelligence along said register through turns linking said cores and experiencing said drive current, the said circuit including a first advance winding threading the major apertures of the cores of one group in a sense to apply clockwise magnetomotive force with respect to the major aperture thereof, a second advance winding threading the major apertures of the cores of the other group in a sense to apply a clockwise magnetomotive force to the core material with respect to the major aperture thereof, a prime winding threading in series by several turns the minor apertures of the cores of both groups in a sense to apply magnetomotive force in a counterclockwise sense relative to said core major aperture and then in series by a lesser number of turns threading the major apertures of the cores of both groups in a sense to apply a clockwise magnetomotive force relative to the major apertures thereof, the said prime windings including a return path to ground isolating said prime windings from the drive currents supplied by said advance windings, a transfer circuit comprised of coupling loops linking the cores of the groups with each coupling loop encircling the outer leg of magnetic material adjacent the core minor aperture to the inner leg of magnetic material adjacent the minor aperture of a succeeding core, each loop having more turns linking the outer leg of magnetic material than linking the inner leg of magnetic material of the succeeding core, the drive circuit when energized in the advance, prime, sequence to the odd and even cores serving to switch flux in a given core to transmit intelligence to a succeeding core via said coupling loops.
